UNITED STATES PATENT OFFICE.

CORNELIUS C. E. VAN ALSTINE AND GEORGE W. GRAHAM, OF PATERSON,
NEW JERSEY.

COMBINED SPINNING, DOUBLING, AND TWISTING MACHINE.

SPECIFICATION forming part of Letters Patent No. 593,866, dated November 16, 1897.

Application filed February 19, 1897. Serial No. 624,122. (No model.)

To all whom it may concern:

Be it known that we, CORNELIUS C. E. VAN ALSTINE and GEORGE W. GRAHAM, citizens of the United States, residing in Paterson, 5 county of Passaic, and State of New Jersey, have invented certain new and useful Improvements in a Combined Spinning, Doubling, and Twisting Machine; and we do hereby declare the following to be a full, clear, and 10 exact description of the invention, such as will enable others skilled in the art to which it appertains to make and use the same, reference being had to the accompanying drawings, and to letters of reference marked thereon, which form a part of this specification. 15

The object of our present invention is to provide a combined spinner, doubler, and twister of simple, strong, and durable construction, reliable in operation, and compact 20 in construction, and thus occupying very little space compared with the several machines at present used to accomplish the above. A further object is to provide said combined spinner, doubler, and twister with a stop-motion 25 whereby when one of the ends breaks its respective bobbin and spindle are instantaneously stopped, and thus reducing the waste to a minimum.

The invention consists in the improved 30 "combined spinner, doubler, and twister," in the receiving-bobbin-carrying reciprocating beam or carriage, its co-operating thread delivery and twisting means, in the stop-motion used in connection with the above, and 35 in the combination and arrangement of the various parts, substantially as will be hereinafter more fully described, and finally embodied in the clauses of the claim.

Referring to the accompanying drawings, 40 in which like letters of reference indicate corresponding parts in each of the several views, Figure 1 is an end elevation of our combined spinner, doubler, and twister with certain parts removed; Fig. 2, a portion of a 45 front elevation of Fig. 1, certain parts being broken away to better illustrate the nature of our said invention; Fig. 3, an enlarged detail view of the top portion of Fig. 2; Fig. 4, a top plan view of Fig. 3; Fig. 5, a detail view 50 of a certain mechanism used in connection with the stop-motion; Fig. 6, a detail view

of the twister proper; and Figs. 7 and 8 are a detail front elevation and top plan view, respectively, of a certain thread-guide, herein-after more fully described.

55

In said drawings, *a* represents one of the end portions of a frame, which end portions are properly secured together by the rails *a'* *a'* and top rails *a²* *a²*. On the rail *a'* are mounted a series of spindles *c²⁴*, carrying the bobbins *c²⁵*, provided at their lower portions with grooved pulleys *c²⁸*, adapted to be operated by the endless belt *c²¹*. Said belt passes over the intermediate grooved pulleys *c⁵⁰* and *c²²* and the driving-pulley *c²⁰*, which latter is 65 mounted on the centrally-arranged shaft *c¹²*, parallel with the rails *a'* and having proper bearings, as clearly shown. The shaft *c¹²*, on which are arranged the loose and fixed driving-pulleys *c¹³*, carries also the grooved wheels *c¹⁴* and *c¹⁸*, transmitting motion to the endless belts *c¹⁵* and *c¹⁹*, respectively, for purposes hereinafter described.

On projecting centrally-arranged lugs of the end portions *a* of the frame are fulcrumed, 75 as at *c⁴*, the upwardly-extending arms *c³*, supporting with their upper ends the beam *c²*, which latter is adapted to carry the receiving-bobbins *c* and also at or near its ends grooved pulleys *c¹⁷* for the belt *c¹⁹*.

80

Each receiving-bobbin *c* is provided at its inner end with a grooved pulley *c⁴⁰*, adapted to be operated by the endless belt *c¹⁹*, and is revolvably mounted on the spindle *c'*, arranged at right angles to the beam *c²* and secured to the 85 central portion of a plate *m*, which latter is mounted on said beam by means of the guide-plates *m⁶*, and is securely held in normal position by a spring-controlled latch *m'*, fulcrumed, as at *m²*, to the top of the beam *c²*, as 90 will be manifest.

To the back of the plate *m* is secured a horizontal pin *m⁷*, arranged in the vertical slot *m⁸* of beam *c²*, and is adapted to engage the fulcrumed latch *m'* when the plate *m* has been 95 released and forced upward by the action of the belt *c¹⁹* to limit the said upward movement, and to thus prevent the striking of the bobbin against the "twister" *b²*. On the lower portion of the plate *m* is also secured a headed pin *m³*, engaged by the looped spring-wire *m⁴*, the free end of which is arranged on the beam 100

c^2 , as clearly shown in Fig. 3. This looped spring-wire is intended to prevent the entire removal of the bobbin-carrying plate m from its guide-plates when a bobbin has to be replaced and the latch m' has been moved out of the path of the pin m^7 .

A series of intermediate grooved pulleys g' are arranged alternately with the grooved pulleys c^{10} to insure a greater frictional contact 10 between the latter and the endless belt c^{19} , as will be manifest.

At right angles to the rail a^2 and secured thereto in any desired manner is the upwardly-extending plate a^3 , provided at certain intervals and in alinement with the spindles c' with vertically-arranged slots a^{20} , penetrated by the hollow shafts b , as clearly shown in Fig. 4.

The hollow shaft b is provided at its inner 20 end with a grooved pulley b' , in frictional contact with the endless belt c^{15} , passing over intermediate pulleys g and over end pulleys c^{16} , which latter are also carried by said plate a^3 . The shaft b has its bearings in the plate g^2 25 and also in the enlarged portion g^4 of bracket or box b^3 , secured to and projecting from the plate g^2 . Said plate and also the bracket or box b^3 are penetrated by a vertical slot g^5 , adapted to coincide, when desired, with the 30 slot g^6 , penetrating the hollow shaft b and its grooved pulley b' .

The plate g^2 is slidably arranged in the guides g^3 and is held in normal position against the spring action of the endless belt 35 c^{15} by means of the fulcrumed spring-controlled latch g^7 , and is limited in its upward movement, when disengaged from said latch, by the pin g^8 , projecting at right angles from the said plate g^2 and adapted to engage the 40 guide-plate g^3 , as clearly shown in Fig. 3.

Projecting from the grooved pulley b' of the hollow shaft b and removably secured to the said pulley by means of the screws g^{22} are the L-shaped arms b^2 b^3 , arranged diametrically 45 opposite each other and provided at their bends and also at their free ends with slotted eyes b^{40} and b^{41} , respectively, forming passages for the doubled and twisted thread T , as will be hereinafter more fully described.

50 At about the center of the machine and at each side thereof are arranged the outwardly-projecting brackets d^2 , carrying two parallel rods d^0 and d' , the inner one of which is provided with a series of eyes d , while the outer 55 one forms the fulcrum for a series of fallers d^4 , carrying at their free ends eyes d^3 , and adapted to engage the horizontal portion h^{50} of the downwardly-extending U-shaped wire h^{10} , pivotally suspended from a needle-pointed lever h^7 . Said lever is fulcrumed, as at h^8 , to a bracket h^9 , extending upwardly from the rail a^2 , and, when in normal position, with its needle-pointed end in engagement with the hammer or weight h^4 , arranged on 60 the arm h^5 , pivotally secured, as at h^6 , to the side of the said rail a^2 . The upper portion of the U-shaped wire h^{10} is slotted and adapt-

ed to receive the needle-pointed end of the lever h^7 , while the shank h^{11} of said U-shaped wire is adapted to prevent the disengagement 70 of the fallers d^4 when out of normal position.

The hammer or weight h^4 is adapted when released from the lever h^7 to strike against the outwardly-projecting portion h^3 of a shaft h^{14} , eccentrically fulcrumed by means of its 75 crank portions h^{13} to a cross-bar h^{20} , arranged on and secured to the under side of the rails a^2 . On the shaft h^{14} are loosely arranged the upwardly-extending plates h and i , provided with vertical elongated slots h^0 and i' , penetrated by the headed pins h' and i' , which latter are secured to and project at right angles from the plate a^3 and beam c^2 , respectively. (See Fig. 5.) The upper portions of the plates i and h are each provided with an 80 indentation adapted to engage the fulcrumed latches m' and g^7 for the plates m and g^2 , respectively, and to thus allow said latches to remain in normal position. Suitable guides 85 b^4 are arranged in front of each hollow shaft and are provided with a series of slotted eyes b^{30} and with a thread-retaining rod b^{31} , as clearly shown in Figs. 7 and 8.

On a shaft c^9 , centrally arranged in suitable bearings in the frame a , is secured a belt-wheel c^{10} , connected through belt c^{11} with the belt-pulley c^0 , mounted on shaft c^{11} . On the shaft c^9 is also arranged a pinion c^8 , meshing into gear-wheel c^7 , mounted on the parallel shaft c^6 , which latter carries eccentric cams 100 c^5 , adapted to strike against antifriction-rollers y , carried by the arms c^3 , to thus operate said arms. The latter are controlled by means of spiral springs f in a manner well understood in the art. 105

The threads T^0 and T' from one set of bobbins c^{25} c^{25} pass through the eyes d (which latter are arranged above and substantially in the center lines of their respective bobbins) and through the eyes d^3 to and over the rod b^6 , arranged horizontally and supported by brackets b^5 , and from there through two of the slotted eyes b^{30} of the guides b^4 into and through the hollow shaft b , from whence they are led as a twisted thread T to the slotted eye b^{40} . The thread is given one wrap around the arm b^2 and after passing through the slotted eye b^{41} is taken up by the bobbin c . 110

From the foregoing it is easily understood that the threads T^0 T' while the bobbins c^{25} 120 are rotated are spun as they leave the same, as the eyes d are arranged above the said bobbins and at a point within the area of their circumference. The said threads are doubled when leaving the guides b^4 and are 125 twisted while passing through the revolving hollow shaft. Should one of the threads break, its respective faller d^4 strikes against the horizontal portion h^{50} of the downwardly-extending wire h^{10} with sufficient force to disengage the needle-pointed lever h^7 from the weight h^4 , which latter drops onto the projecting end h^3 of the shaft h^{14} and operates 130 the same—that is to say, said shaft by means

of its eccentrics h^{18} is moved downward, carrying with it the slotted plates h and i . Said plates then force the fulcrumed latches g^7 and m' out of their respective indentations and thus out of the path of the plates g^2 and m , respectively. The said plates, now released, are sprung upward by the action of the endless belts c^{15} and c^{19} , and the grooved pulley b' of the hollow shaft b and the grooved pulley c^{40} of the bobbin c are thus thrown out of operative engagement with their respective belts. After the break has been repaired the various parts are returned to their normal operative positions, as will be manifest.

15 It may be remarked that the bobbins in this machine are interchangeable—that is to say, the bobbins c^{25} and their grooved pulleys c^{33} are uniformly constructed with the bobbins c and their pulleys c^{40} , so that the latter, when filled, can be placed on the spindles c^{24} on rail a' , and their threads can be again combined by subjecting them to the operation heretofore described.

We do not intend to limit ourselves to the precise construction shown and described, as various alterations can be made without changing the scope of our invention; but

What we claim as new, and desire to secure by Letters Patent, is—

30 1. A combined spinning, doubling and twisting machine, consisting of a frame, a reciprocating beam in said frame, a series of fulcrumed arms supporting said beam, a shaft in said frame, a series of cams on said shaft and adapted to operate said fulcrumed arms, means for revolving said shaft, a series of receiving-bobbins carried by said beam and at right angles thereto, a series of hollow shafts in said frame and in alinement with the receiving-bobbins, an L-shaped arm projecting from the inner end of each shaft and in close proximity with its respective bobbin, a series of delivery-bobbins also arranged in the frame, a series of intermediate eyes between the delivery-bobbins and the hollow shafts, and means for revolving the delivery and receiving bobbins and the hollow shafts, all said parts, substantially as and for the purposes described.

50 2. A combined spinning, doubling and twisting machine, consisting of a frame, a reciprocating beam in said frame, means for operating said beam, a series of plates slidably arranged on said beam, a stationary spindle on each plate and projecting at right angles therefrom, a receiving-bobbin revolvably arranged on each of said spindles, a series of hollow shafts in said frame and in alinement with the receiving-bobbins, an L-shaped arm projecting from the inner end of each shaft and in close proximity with its respective bobbin, a series of delivery-bobbins also arranged in the frame, a series of intermediate eyes between the delivery-bobbins and the hollow shafts, and means for revolving the delivery and receiving bobbins and the hol-

low shafts, all said parts, substantially as and for the purposes described.

3. A combined spinning, doubling and twisting machine, consisting of a frame, a reciprocating beam in said frame, a series of receiving-bobbins carried by said beam and at right angles thereto, an upwardly-projecting plate supported by the frame and substantially parallel with the beam and provided with a series of vertical slots, a series of plates slidably arranged on said upwardly-extending plate and in front of said slots, a hollow shaft revolvably arranged in each of said plates, an L-shaped arm projecting from the inner end of the shaft and in close proximity with its respective bobbin, a series of delivery-bobbins also arranged in the frame, a series of intermediate eyes between the delivery-bobbins and the hollow shafts, and means for revolving the delivery and receiving bobbins and the hollow shafts, all said parts, substantially as and for the purposes described.

4. A combined spinning, doubling and twisting machine, consisting of a frame, a reciprocating beam in said frame, means for operating said beam, a series of receiving-bobbins carried by said beam and at right angles thereto, a series of hollow shafts in said frame and in alinement with the receiving-bobbins, an L-shaped arm projecting from the inner end of each shaft and in close proximity with its respective bobbin, a series of delivery-bobbins also arranged in the frame, two horizontal rods in the frame, a series of eyes on one of said rods and above and substantially in the center lines of their respective delivery-bobbins, a series of fallers fulcrumed on the other rod, a downwardly-projecting U-shaped arm adapted to be engaged by its respective faller, a fulcrumed lever pivotally connected with said U-shaped arm, an eccentrically-arranged shaft in the frame and at right angles to the beam, a fulcrumed weight adapted to operate said shaft and in engagement with the fulcrumed lever, and means operated by said shaft for controlling the receiving and delivery bobbins, and means for revolving the delivery and receiving bobbins and the hollow shafts, all said parts, substantially as and for the purposes described.

5. A combined spinning, doubling and twisting machine, consisting of a frame, a reciprocating beam in said frame, means for operating said beam, a series of plates slidably arranged on said beam, means for locking said plates in normal position, a bobbin carried by each of said plates, a series of delivery-bobbins also arranged in the frame, two horizontal rods in the frame, a series of eyes on one of said rods and above and substantially in the center lines of their respective bobbins, a series of fallers fulcrumed on the other rod, a downwardly-projecting U-shaped arm adapted to be engaged by its respective faller, a fulcrumed lever pivotally connected with said U-shaped arm, an eccentrically-arranged

shaft in the frame and at right angles to the beam, a fulcrumed weight adapted to operate said shaft and in engagement with the fulcrumed lever, means operated by said shaft for controlling the locking mechanism, a hollow shaft in front of each receiving-bobbin, and means for revolving the receiving and the delivery bobbins and the hollow shafts respectively, all said parts, substantially as and for the purposes described.

6. The combination with a frame, of a beam in said frame, a series of vertically-guided plates on said beam, a fulcrumed spring-controlled latch for each of said plates and adapted to lock the same, a vertical plate provided with an indentation in engagement with each latch, an eccentrically - arranged shaft arranged in said frame and at right angles to the beam and supporting said vertical plates, and means for operating said shaft, all said parts, substantially as and for the purposes described.

7. The combination with a frame, of a beam in said frame, a series of vertically-guided plates on said beam, a fulcrumed spring-controlled latch for each of said plates and adapted to lock the same, a vertical plate provided with an indentation in engagement with each latch, an eccentrically-arranged shaft in said frame and at right angles to the beam and supporting said vertical plates, and having one of its ends bent outward, a weight adapted to engage the outward-bent end of the shaft, a fulcrumed needle-pointed lever in engagement with said weight, and means for operating said lever, all said parts, substantially as and for the purposes described.

8. The combination with a frame, of a series of delivery-bobbins in said frame, a series of receiving-bobbins also in said frame and

substantially at right angles to the delivery-bobbins, a series of revolving hollow shafts intermediately arranged between said series of bobbins and in alignment with their respective receiving-bobbins, an L-shaped arm projecting from the inner end of each hollow shaft, a guide in front of the forward end of each shaft, a series of eyes intermediately arranged between said guides and the delivery-bobbins and above and substantially in the center lines of the latter, and means for revolving the receiving and delivery bobbins and the hollow shafts, all said parts, substantially as and for the purposes described.

9. The combination with a frame, of a reciprocating horizontal beam in said frame, a series of stationary spindles on said beam and at right angles thereto, a rail parallel with the beam and on one side of the frame, a series of vertically-arranged spindles on said rail, interchangeable bobbins on said series of spindles, a series of revolving hollow shafts intermediately arranged and carried by the frame, an L-shaped arm projecting from the inner end of each shaft, a guide in front of each shaft, a series of eyes intermediately arranged between said guides and the spindles on the rail and above and substantially in the center line of the said spindles, and means for revolving the bobbins and the hollow shafts, all said parts, substantially as and for the purposes described.

In testimony that we claim the foregoing we have hereunto set our hands this 30th day of January, 1897.

CORNELIUS C. E. VAN ALSTINE.
